(57) **CLAIM**

The ornamental design for a cookware elongated handle, as shown and described.

DESCRIPTION

FIG. 1 is a perspective view from above of the 1st embodiment of the “cookware elongated handle”, showing my new design;

FIG. 2 is a top plan view of the 1st embodiment thereof;

FIG. 3 is a front elevation view of the 1st embodiment thereof;

FIG. 4 is a side elevation view of the 1st embodiment thereof;

FIG. 5 is a bottom plan view of the 1st embodiment thereof;

FIG. 6 is a back elevation view of the 1st embodiment thereof;

FIG. 7 is a perspective view from below of the 1st embodiment thereof;

FIG. 8 is a perspective view from above of the 2nd embodiment thereof;

FIG. 9 is a top plan view of the 2nd embodiment thereof;

FIG. 10 is a front elevation view of the 2nd embodiment thereof;

FIG. 11 is a side elevation view of the 2nd embodiment thereof;

FIG. 12 is a bottom plan view of the 2nd embodiment thereof;

FIG. 13 is a back elevation view of the 2nd embodiment thereof; and,

FIG. 14 is a perspective view from below of the 2nd embodiment.

The broken lines in FIGS. 1, 3, 4, 6, 7, 8, 10, 11, 13 and 14 are for illustrative purposes only, depicting the environment of the new design, forming no part thereof as claimed.
